DANIEL P. PRESCOTT, OF VERNON, VERMONT, ASSIGNOR OF ONE-HALF TO
EDWIN F. BROOKS, OF BRATTLEBOROUGH, VERMONT, AND JAMES W.
SHANKS, OF PALMER, MASSACHUSETTS.

CAR-COUPING.

SPECIFICATION forming part of Letters Patent No. 307,729, dated November 4, 1884.

Application filed March 10, 1884. (No model.)

To all whom it may concern:

Be it known that I, DANIEL P. PRESCOTT, a citizen of the United States, residing at Vernon, in the county of Windham and State of 5 Vermont, have invented new and useful Improvements in Car-Couplings, of which the following is a specification.

This invention relates to improvements in car-couplings, the object being to combine with 10 couplings constructed substantially like the ordinary "link-and-pin" couplings improved self-coupling devices which may or may not be brought into use and which do not interfere with the use of the link and pin.

15 A further object of this invention is to provide such improved self-coupling devices for cars as permits of considerable difference of height between the couplings of two cars without interfering with the proper interlocking of 20 the couplings, and to provide such an improved construction and arrangement of automatic hook-couplings as permits of great freedom of movement to the cars united thereby when running around curves, and which are 25 easily and conveniently uncoupled when the cars are standing on a sharp curve of the road.

In the drawings, Figure 1 illustrates a pair 30 of car-couplings embodying my invention, one of which is shown attached to a car, the latter being provided with devices for elevating and lowering the coupling-hook. Fig. 2 is a side elevation of the coupling. Fig. 3 is a plan view; and Fig. 4 illustrates a coupling on the 35 end of the car, having the hook drawn up against the car.

In the drawings, A indicates an end of a car having attached thereto in any well-known manner the coupling draw-bar *a*, which is provided with the usual mouth, *w*, and pin-hole *x*, for the purpose of employing therewith, if need be, the link *y* and pin *z* in the ordinary way. The coupling as thus described and shown is substantially the common link-and-pin coupling. To adapt this coupling, however, to serve likewise as a self or automatic coupler, and to be with equal facility employed in connection with a coupling not provided with the automatic feature thereof, the draw-

bar has applied thereto a coupling hook-bar, as hereinafter described. The draw-bar *a* has 50 its thickness reduced from its end rearward for a suitable distance to receive upon the upper side thereof the coupling hook-bar *b*. The hook-bar *b* is adapted to have its rear end come against the abutment *K* on the upper side of 55 the bar *a*, its thickness being about equal to the height of said abutment, and its width about the same as that of the draw-bar *a*. The hook-bar *b* is pivotally secured to the draw-bar by the staple *d* or other suitable means, whereby 60 it is capable of having free vibratory movements in a horizontal and vertical plane, and is thereby so secured to the draw-bar as to resist any tractional strain to which it may be submitted. The free or outer end of the hook-bar *b* is double-hooked—that is to say, it is 65 made of a barbed spear-head shape, a hook extending from edge to edge on each side thereof and its end terminating in a thin edge. The hook-bar *b* has a chain, *e*, attached to it, which 70 chain extends back of a suitable guide-roller and up to the roof of the car, where it is attached to a lever, *n*, and by swinging the latter over onto the car-roof the hook-bar can be drawn up against the end of the car, as in Fig. 75 4, and there held; or it can by a person on the car-roof be manipulated, if need be, to facilitate its engagement with another hook-bar.

Pivoted on the end of car *A* are two levers, *v*, whose outer ends extend beyond the sides 80 of the car, and their inner ends, which terminate near chain *e*, are attached thereto by chains *o*, so that the hook-bar may thereby be swung up and down.

The above-described improved additional 85 coupling devices are applied to the usual link-and-pin coupling, in order that the inconvenience of coupling the latter, which are by far the most common, with a self-coupler, may be avoided, and to the end that a car provided 90 with the coupling herein shown and described may be easily coupled to a car having only the link-and-pin coupling, and vice versa.

The operation of my improvements is easily 95 understood from the drawings by any one skilled in the art. When two couplings, as in

Fig. 1, come together, it is immaterial which of the bars *b* is uppermost. This will be determined by any difference in height there may be between the ends of the draw-bars. The 5 incline *c* on the latter guides the end of hook *b* upward as the latter strikes bar *a*. The brakeman, either on the roof or on the ground, can work the hook-bars *b* by the lever *n*, or by one of the levers *v*, if need be, to bring them 10 into proper locking position without going between the cars; or he can by like means uncouple the same. The free vibratory movement horizontally which the hook-bars are permitted to have, as shown in Fig. 3, prevents 15 any such undue lateral strain being brought upon them while a train is standing on a curve as to interfere with easily disconnecting the hook-bars, the latter being subjected while in practical use to tractive strain only.

20 What I claim as my invention is—

1. The combination, with the draw-bar *a*, provided with the mouth *w*, the abutment *K*, and pin-hole *x*, of the hook-bar *b*, pivoted to the upper side of said draw-bar adjacent to said abutment, and capable of horizontal and vertical vibratory movements, substantially as set forth. 25

2. The combination, with the draw-bar *a*, provided with the mouth *w*, the abutment *K*, and pin-hole *x*, of the hook-bar *b*, pivoted to 30 the upper side of said draw-bar adjacent to said abutment, and capable of horizontal and vertical vibratory movements, and means, substantially as described, for lifting and lowering said hook-bar, all as set forth.

DANIEL P. PRESCOTT.
